United States Patent Office.

WILLIAM C. DAVIS, OF CINCINNATI, OHIO.

Design No. 3,951, dated April 5, 1870.

DESIGN FOR A COOKING-STOVE.

The Schedule referred to in these Letters Patent and making part of the same

I, WILLIAM C. DAVIS, of Cincinnati, in the county of Hamilton and State of Ohio, have invented a new and original Design for a Cooking-Stove, of which the following is a specification.

My invention consists in the form and pattern of the various parts of the stove represented in the accompanying print, which forms a part of this specification.

Claim.

I claim the design for a cooking-stove, substantially as specified.

In testimony of which invention I hereunto set my hand.

Witnesses:

GEO. H. KNIGHT,
JAMES H. LAYMAN.
